Primary Examiner — Rhea Shields(74) *Attorney, Agent, or Firm* — Zhihua Han(57) **CLAIM**

The ornamental design for a lumbar vertebrae correcting instrument, as shown.

DESCRIPTION

FIG. 1 is a perspective view of the lumbar vertebrae correcting instrument showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of the design shown in an open position.

1 Claim, 8 Drawing Sheets(56)
